UNITED STATES PATENT OFFICE.

NATHAN MNUSKIN, OF SAN PEDRO, CALIFORNIA.

REMOVABLE-COIL BED-SPRING.

1,010,667.

Specification of Letters Patent.

Patented Dec. 5, 1911.

Application filed July 29, 1911. Serial No. 641,337.

To all whom it may concern:

Be it known that I, NATHAN MNUSKIN, a subject of Russia, residing at San Pedro, California, have invented a new and useful 5 Removable-Coil Bed-Spring, of which the following is a specification.

My invention relates to a new and improved construction in springs of the class ordinarily used for beds, couches, and in 10 upholstering.

The object of the invention is to provide a simple, durable spring composed of any desired number of coils, any one of which may be readily removed and replaced when 15 desired.

The various features of the invention are herein fully described and are illustrated in the accompanying drawings in which—

Figure 1 is a bottom plan view of a bed 20 spring. Fig. 2 is an inside view of a spring holder. Fig. 3 is an outside view of the same holder. Fig. 4 is a side view of one of the coils attached to the top and bottom holders.

25 In the several views like characters refer to like parts.

Referring to the details of construction: 1 is a coil spring similar to the ordinary coil spring. At the top and bottom of the spring 30 the wire is formed in a ring and the end of the wire shaped into an eye 2. This eye is made large enough to slide freely along the wire which it encircles. In this way a ring is formed which may be expanded by sliding 35 the eye along the wire as shown by the dotted lines in Fig. 2.

The holder provided for securing the spring consists of radial arms 3, of which four are shown, connected at the center and 40 having lugs 4 formed on the ends of each, equidistant from the center, with openings 5 to receive the longitudinal and transverse wires 6 and 7 respectively. Lips 8 are formed on the lugs for retaining the expandible rings formed on the coil springs. 45

9 is the outer frame to which the transverse and longitudinal wires are attached after the usual fashion.

The use and operation of my device is as follows: Top and bottom frames of the general type shown are provided. Cross wires 6 and 7 are stretched from side to side and from end to end with both wires at each intersection threaded through the lugs 4. After the holders are thus secured in place 55 in each frame the rings on the end of the springs are expanded enough to allow them to pass over the lips 8 after which the ring is released and closes against the lugs 4. When the coils are all thus secured to the 60 holders in one frame the other is placed on top of coils and secured in like manner. When desired a single spring may be detached and removed without disturbing the others by expanding the rings on the two 65 ends and lifting over the lips 8; at other times the two ends of each coil are firmly held in place between cross wires, lugs and lips.

The cross wires are shown intersecting 70 each other at right angles and the arms of the holder are likewise placed at right angles. If more wires are used in such manner that three or more intersect at each crossing the arms are varied accordingly and 75 their direction made to correspond with that of the wires.

Having thus described my invention what I claim as new and desire to secure by Letters Patent is:

In a device of the character described: top and bottom frames; cross wires stretched between the sides and the ends of said frames; holders attached to the cross wires at each intersection, provided with lugs and lips; 85 a plurality of coil springs adapted to be retained between said holders; and expandible rings formed on the two ends of each coil adapted to engage the lugs on the said holders.

NATHAN MNUSKIN.
